a corporation of Delaware

Application November 14, 1947, Serial No. 786,106

49 Claims. (Cl. 93—3)

1

This invention relates to a machine and method for making containers. More particularly it pertains to a machine and method for forming a container having a pellet or capsule of dispersible material therein for coloring the contents of such a container when the same is filled with a semi-solid, viscous or plastic mass of oleaginous material such as, for example, oleomargarine.

It is an object of the invention to provide a machine and method for making heat-sealable containers of tube-like construction which are transversely sealed at one end and which have a capsule or pellet of dispersible material secured against an inner wall surface thereof by a heat-sealable capsule holding or patch member that will permit the pellet, or capsule contents, to be dispersed and thoroughly intermingled with the contents of the container.

Another object of the invention is to provide a mechanism and method for feeding capsule holding members for such containers successively into position onto movable mandrels which are adapted to receive the same in capsule holding position for subsequent attachment thereof within the containers against an inner wall surface thereof.

Another object of the invention is to provide a mechanism and method for feeding capsules for such containers successively and selectively onto capsule holding members before securing them as a unit within the containers.

Another object of the invention is to provide a mechanism and method for feeding such containers, or container tubes, into position so that an inner wall surface thereof overlies each capsule and its associated holding member in order to secure the same within the container.

Another object of the invention is to provide a mechanism and method for securing the capsule holding members to the inner wall surfaces of such containers, or container tubes, preferably by the application of heat and pressure.

Other objects of the invention will in part be obvious and will in part appear hereinafter.

The invention accordingly comprises the several steps and the relation of one or more of such steps with respect to each of the others, and the apparatus embodying features of construction, combinations of elements and arrangement of parts which are adapted to effect such steps, all as exemplified in the following detailed disclosure, and the scope of the application of which will be indicated in the claims.

For a fuller understanding of the nature and objects of the invention reference should be had to the following detailed description taken in con-

nection with the accompanying drawings, in which:

Fig. 1 is a front elevational view of a preferred type of machine which exemplifies the principles of the present invention;

Fig. 2 is a plan view of the machine shown in Fig. 1;

Fig. 3 is an end elevational view of the machine depicted in Figs. 1 and 2, looking from right to left of those figures;

Fig. 4 is a side elevational view of a perforating and cutting mechanism for preparing capsule holding members from a web of suitable material and for feeding them onto cooperatively associated mandrels adapted to receive the same in capsule holding position;

Fig. 5 is a sectional view of the perforating and cutting mechanism, taken along the line 5—5 of Fig. 4 and looking in the direction of the arrows;

Fig. 6 is a side view of one of the mandrels and a portion of the perforating and cutting mechanism taken along the line 6—6 of Fig. 4, the mandrel being disposed in position for receiving the capsule holding member as it is cut off by the knife;

Fig. 7 is a more detailed plan view of one of the mandrels;

Fig. 8 is a longitudinal sectional view of the mandrel depicted in Fig. 7 with an intermediate portion removed therefrom for clarity in illustration;

Fig. 9 is an end elevational view of the mandrel shown in Figs. 7 and 8 and looking from right to left of those figures;

Fig. 10 is a sectional elevational view taken transversely of the machine, along the line indicated at 10—10 of Fig. 2, showing the capsule feeding mechanism and the plunger device for forming pockets in the capsule holding members as the latter are presented by the successive mandrels for receiving the capsules from the feeding mechanism, the plunger device also operating to tamp the capsules in the pockets formed in the holding members;

Fig. 11 is a side elevational view of the capsule feeding mechanism, the view being taken from the rear side of the machine;

Fig. 12 is a side elevational view of the plunger device for forming the pockets in the capsule holding members and tamping the capsules in the pockets, the view being taken from the front side of the machine;

Fig. 13 is a detail view of a capsule ejector element for selectively transferring individual capsules from the feed mechanism to a chute for

delivery by gravity into a pocket formed in the capsule holding member on the mandrel while the latter is positioned below the plunger device;

Fig. 14 is a detail view of a clover shaped cam and follower arrangement, depicted in Fig. 11 in dotted lines, for actuating the feeding hopper, the view being taken along the line 14-14 of Fig. 10 and looking in the direction of the arrows;

Fig. 15 is a detail view illustrating a heart-shaped cam and follower arrangement, also depicted in Fig. 11 in dotted lines, which is mounted on the same shaft as the clover-shaped cam, for operating the capsule or pellet ejector device shown in Fig. 13, the view being taken along the line 15-15 of Fig. 10 and looking in the direction of the arrows;

Fig. 16 is an elevational view, taken on the line 16-16 of Fig. 2, showing the mechanism for feeding tube stock and cutting it into container forming lengths preparatory to delivery to the mandrels;

Fig. 17 is a partial transverse section, taken on the line 17-17 of Fig. 2 showing the mechanism which cooperates with the container forming mechanism of Fig. 16 to deliver the container forming tube lengths onto the successive mandrels so that the inner wall surface of each container will overlie the capsule and its associated holding member, which have previously been delivered onto the mandrel, to permit the holding member to be secured to the container wall, preferably by the application of heat and pressure;

Fig. 18 is a transverse sectional view, taken along the line 18-18 of Fig. 16 and looking in the direction of the arrows;

Fig. 19 is an elevational view, taken along the line 19-19 of Fig. 2, of a mechanism for heat sealing a capsule holding member into position against the inner wall surface of a container forming tube length and simultaneously therewith heat sealing marginally across the trailing end of the tube length to close the same and provide an open-ended tube-like container ready for filling;

Fig. 20 is an end elevational view, taken along the line 20-20 of Fig. 2, of the heat sealing mechanism;

Fig. 21 is a diagrammatical view illustrating the perforating and cutting mechanism in operation on a continuously unwinding tape, providing a slack between feed rollers and the cutting blade and intermittently shearing off perforated capsule holding members for deposit in timed relation onto the advancing mandrels;

Fig. 22 is a diagrammatic representation illustrating the action of an intermittently moving mandrel (A through D) from the time it advances to receive the capsule holding member until it is ready for the operation of the plunger device which forms the pocket for the capsule and also illustrating (D' through D⁴) the operation of the plunger device and the capsule feeding mechanism in forming the pocket, feeding the capsule and tamping the capsule into the pocket ready for receipt of the container forming tube length;

Fig. 23 is a diagrammatical view of a continuously unwinding tube of container material as it passes between air-blocks to maintain an air bubble therein to separate the opposed tube faces;

Fig. 24 is a sectional view on the line 24-24 of Fig. 23 illustrating the separation of the tube walls by the air bubble;

Fig. 25 is a diagrammatic view illustrating the

tube feeding and cutting mechanism showing the feeding arms for the cut tube lengths preparatory to placing a tube length over a mandrel with a capsule and its associated holding member on the mandrel;

Fig. 26 (E, F and G) is a diagrammatic view illustrating the placing of a container forming tube length on a mandrel so that one inner wall surface of the container overlies a capsule and its holding member and also illustrating the sealing of the same into position against the inner wall surface of the container, as well as the sealing of the trailing end of the tube length to complete the formation of the container;

Fig. 27 shows a completed container; and

Fig. 28 is a transverse section, taken on the line 28-28 of Fig. 27.

The nature of the invention can readily be understood from a brief analysis of Figs. 21 to 28. Figs. 21, 22, 23, 25 and 26 constitute a diagrammatic illustration of the sequence of operations of the preferred machine and the steps of the method involved in forming the container on the machine.

In Fig. 21 there is shown a tape which is continuously unwound from a supply roll, perforated by the perforating device and then intermittently fed to a cutting knife where capsule holding members are cut from the tape to be deposited on the mandrels.

In Fig. 22 a mandrel is shown (A) being advanced with the hold-down for the capsule holding member being raised (B) from its downward position to an out-of-the-way position. The capsule holding member is deposited onto the mandrel (C) whereupon the hold-down returns to operative position to retain the capsule holding member in place (D). Thereafter, a plunger comes into operative position (D'), depressing the capsule holding member to form a pocket (D²) as a capsule comes down an adjacent chute which leads to a hopper from which individual pellets are ejected by an ejection member. After the plunger is reciprocated (D³) the capsule falls into the opening of the pocket formed in the holding member. Thereupon the plunger returns (D⁴) to tamp the capsule into the pocket, the plunger alternately having a foreshortened stroke to permit of this action.

The next operation is to place a container forming tube length over the mandrel so that one inner wall surface of the container overlies the capsule and its holding member. In Figs. 23 to 25 a continuous web of tube material is fed through an air block where an air bubble initially separates the walls of the tube and thence to a cutting blade which partially severs the tube into container forming lengths. The lengths are separated, one by one, from the leading end of the tube by a reciprocating pair of feeding arms which grip the outside surfaces adjacent the end of the tube, slightly open the end of the tube and rapidly advance to completely detach the end length from the tube and strip it over the mandrel (E). The tube length is held in position by hold-down arms on the mandrel and the hold-down for the capsule holding member is retracted after which the capsule holding member is sealed to the overlying wall of the tube length (F'). The trailing end of the container forming tube length is preferably simultaneously sealed to complete the formation of the container after which it is released by movement of the hold-down arms (G). The completed container which

is more clearly shown in Figs. 27 and 28 is then removed from the mandrel.

Referring more particularly to Figs. 1 to 20 of the drawings, the separate mechanisms which are cooperatively associated in the illustrated machine for carrying out the various operations involved in forming the container bear the following captions: Drive Mechanism (Figs. 1 to 3, particularly); Capsule Holding Member Perforating and Cutting Mechanism (Figs. 4, 5 and 6); Capsule Feeding Mechanism (Figs. 10 to 15); Container Feeding Mechanism (Figs. 16, 17 and 18); and Sealing Mechanism (Figs. 19 and 20).

For convenience in illustration and reference to structural parts the Drive Mechanism will start with reference numeral 10, the Capsule Holding Member Perforating and Cutting Mechanism will start with reference numeral 100, the Capsule Feeding Mechanism will start with reference numeral 200, the Container Feeding Mechanism will start with reference numeral 300, and the Sealing Mechanism will start with reference numeral 400.

Drive mechanism

Referring to Figs. 1 to 3, the machine comprises a frame structure having mounted thereon the various mechanisms referred to, all of which are preferably driven in timed relation from a single motor 10. Motor 10 drives the transverse shaft 11 by means of the pulley and belt 12. Gear 13 which is secured on the other end of the shaft 11 drives gear 14 on one end of transverse shaft 15. Gear 16 on the other end of shaft 15 drives gear 17 on shaft 18, on the outer end of which there is the driving gear of a Geneva mechanism 19 which intermittently drives the shaft 20. Gear 21 on shaft 20 drives gear 22 on the shaft 23 which operates the rectilinear traverse or conveyor carrying the series of mandrels.

The gear 13 on the shaft 11 also drives gear 24 which is fixed on the transverse shaft 25. At the far side of the machine (Figs. 2 and 3) the shaft 25 carries a bevel gear 26 which meshes with bevel gear 27 on the shaft 28. The shaft 28 drives the vertical shaft 29 by means of bevel gears 30 and 31. The shaft 29 (Figs. 2, 3, 10 and 11) is connected by means of bevel gears 32 and 33 to a transverse shaft 34 carrying gear 35 which drives gear 36 on the transverse cam shaft 37 which operates the Capsule Feeding Mechanism and the associated plunger device for forming the pockets in the capsule holding members.

The shaft 34 (Figs. 2, 3, 4 and 5) extends to and operates the Capsule Holding Member Perforating and Cutting Mechanism. The gear 38 on the shaft 34 drives gear 39 on the shaft 40 which operates the web perforating device. The gear 38 also drives gear 41 on shaft 42 from which the remainder of the mechanism is operated by conventional driving connections.

The transverse shaft 25 (Figs. 2 and 3) extends forwardly of the machine along the Container Feeding Mechanism (Figs. 2 and 16) and is connected by means of bevel gears 43 and 44 with shaft 45. The shaft 45 is connected by means of gears 46, 47 and 48 with the shaft 49 from which the mechanism for feeding the tube is operated by conventional driving connections.

While the machine is illustrated as provided with the drive mechanism described, it will be appreciated that more than one motor may be used to drive the various mechanisms in the proper timed relation and that other equivalent driving means may be utilized.

Capsule holding member perforating and cutting mechanism

Referring now to Figs. 4, 5 and 6 of the drawings, a tape 100 is unwound from a reel 101 (see Fig. 1) and passed over idler rollers 102 and 103 mounted to rotate in a frame support or plate 104.

The tape 100 passes through a perforating device indicated generally at 105. This consists of a vertical shaft 106 mounted to slide in a pair of spaced bushings 107 and 108. The bushings 107 and 108 are mounted on a plate 109 which is fixed at its lower end to the end of a rotatably mounted shaft 110. The top end of the shaft 106 is connected to an eccentric 111 secured to the driven shaft 40. At the bottom end of the shaft 106 there is a head 112 having mounted therein a gang of perforating needles 113. The needles 113 are adapted to pass through a perforated stripping plate 114 and a web support plate 115, also perforated. The plates 114 and 115 are secured to the end of the rotatably mounted shaft 110, in the same manner as plate 109. The tape 100 passes between the stripping plate 114 and the support plate 115. The eccentric 111 reciprocates the shaft 106 and also imparts to the plate 109 an oscillating movement about the axis of the shaft 110 as a pivot. As a result of this operation the needles travel in an orbital path so that they penetrate the web 100 and move along with the web, at approximately the same speed as the web, as they descend into the perforations in the support plate 115, after which they are withdrawn to repeat the perforating operation. In this manner the tape 100 is provided with spaced rows of perforations while it is moving continuously and the elasticity and static characteristics of the material are overcome without tearing or making undue enlargements and without retarding, buckling or doubling the tape.

The tape is next severed to provide holding members for the capsules, which holding members are then deposited on the mandrels. In Fig. 4 a mandrel is indicated in position to receive the holding member.

In the particular embodiment of the invention illustrated (Figs. 1, 2, 3) a plurality of mandrels 50 are mounted in any suitable manner on a flexible conveyor, chain and sprocket arrangement or the like, preferably to travel in a rectilinear traverse as illustrated in the drawings. In this respect, any suitable construction for practicing the invention may be chosen by those skilled in the art to satisfy their particular requirements. The mandrels are moved in their rectilinear traverse between the frames of the machine by the drive mechanism previously described. The mandrels are first successively moved to the position indicated in Figs. 3, 4 and 6 where each mandrel receives a capsule holding member.

The tape 100, having been perforated, advances continuously between the drive rollers 116 and 117 at a predetermined rate of speed determined by the length of the holding member, after which an intermittent motion is imparted to the tape. There is a pause in the advance of the tape so that a capsule retaining member can be cut therefrom. The intermittent motion is imparted to the tape by permitting a slack to occur in the tape, as at 118, after the perforated tape leaves the rollers 116 and 117. The slack 118 is intermittently taken up and the tape advanced by 70 means of draw rollers 119 and 120. It will be

noted that the draw roller 119 is of constant diameter whereas draw roller 120 is segmental and only a portion of its circumference will contact the face of the roller 119. By such means the slack 118 is controlled and taken up intermittently to feed the perforated tape intermittently to the cutting device.

The cutting device or mechanism comprises an anvil blade or knife 121 and a cooperating movable blade 122 which is pivoted at 123 to the end of a knife holding arm 124. The blade 122 is urged into alignment with the edge of the anvil 121 by a compression spring 125 against an adjustable stop member 126 secured on a lug 127 depending from the arm 124. The arm 124 is keyed to a shaft 128 on one side of the frame plate 104. On the other side of the frame plate 104, shown in dotted line position (Fig. 4) is an actuating arm 129 also keyed to the shaft 128, and having a cam follower 130 which rides a cam 131 on driven shaft 34 and imparts movement to the arm 124 and 129. The knife is thus mounted to obtain a shearing cut. A stripper plate 132 is mounted in spaced relation above the base plate and lower knife holder 133. The plate 132 is pivoted at 134 and provided with an upstanding arm 135 which bears against an eccentric 136, by means of which the position of the plate 132 may be adjusted. The plate 132 overcomes static and guides the tape between the knives 121 and 122. The mechanism feeds continuously the web or tape, and changes the motion of feed from a continuous to an intermittent motion, to permit capsule holding members to be cut therefrom. The holding members are delivered onto each successive mandrel in timed relation to the intermittent movement of the mandrels.

Capsule feeding mechanism

Referring now to Figs. 10 to 15, there is provided a hopper 200 having a gate plate 201 therein spaced from the bottom of the hopper to permit capsules 202 to pass thereunder in a single layer into an assembly chamber 203. The hopper 200 is supported at its rear end by a compound link arrangement comprising a link 204 pivoted at 205 to the bottom of the hopper and a link 206 pivoted at 207 to the link 204 and also pivoted at 208 to a rear side frame plate 209 of the machine. The pivot point 207 is locked after the hopper 200 is properly adjusted to a slope that will cause the capsules to feed in a single layer. The links 204 and 206 then act as a single link. The hopper 200 is reciprocated or rocked to bring about the feeding of the capsules 202. This is accomplished by means of a clover shaped cam 210 (Figs. 11 and 14) secured to the driven shaft 37. The clover cam 210 actuates an arm 211 of a bell crank which is pivoted on the shaft 212, the shaft 212 extending transversely between the side frame plates 209 and 213 of the machine. The end of the actuating arm 211 is provided with a follower or roller 214 for engaging the cam 210. The other arm 215 of the bell crank is pivotally secured to the front end of the hopper at 216. A spring 217 is secure at one end to the hopper 200 at 216 and at the other end to the frame plate 209. The spring 217 holds the cam roller 214 against the cam 210 and insures uniform motion of the hopper 200. The arm 216 of the bell crank is connected by a cross or tie plate 218 with a cooperating hopper supporting arm 219 which is pivotally mounted at one end on the transverse shaft 212 and at its other end on the bottom of the hopper 200. The clover shaped cam 210 op-

erates to cause a rocking or reciprocating motion to be imparted to the hopper 200. The purpose of the rocking motion is to agitate the capsules 202 which are in a single layer in the assembling chamber 203 to fall through the hole 220 into the hopper spring conduit 221 to provide a stack for the feeding mechanism.

Another actuating arm or plate 222 is rotatably mounted on the shaft 212 (Figs. 10, 11 and 15) and is provided with a cam follower 223 riding a heart-shaped cam 224 secured to the driving shaft 37. A spring 225 is secured at one end to the plate 222 and at the other end to the frame of the machine to hold the follower 223 against the cam 224. Linked to the plate 222 is a slideable plunger or capsule ejector member 226 having a U-shaped plate 227 at the outer end (Figs. 11 and 13) whereby to remove individual capsules 202 from the stack in the conduit 221 and selectively to deposit them in the chute 228. The ejector 226 is mounted to reciprocate in a suitable head, or bearing 229 which receives the lower end of the conduit 221. As the plate 222 is actuated by the cam 224 it imparts a reciprocating motion to the ejector 226. With each stroke in a forward direction a capsule 202 is removed from the bottom of the aligned stack in the conduit 221 and delivered to the chute 228. The chute is angularly disposed with respect to the ejector 226 and terminates above and adjacent the capsule holding member which has already been deposited on the respective mandrel.

Before the capsule 202 finds its way down the chute 228 to the capsule holding member a pocket is formed in the latter. This, preferably, is accomplished by means of a reciprocating plunger device indicated generally at 230 (Figs. 10 and 12). It comprises a vertical shaft 231 which is mounted in spaced bearings 232 and 233 extending from a stationary supporting plate 234 which is secured to the frame of the machine. The shaft 231 is spring loaded by means of a spring 235 and a collet 236 on the shaft 231 holding the spring in energized position. The top end of the shaft 231 is connected to one arm 237 of a bell crank pivotally mounted on the transverse shaft 212, the other arm 238 of the bell crank carrying a cam follower 239 riding a cam 240 secured to the driving shaft 37. It will be observed by reference to Fig. 12 that this cam has a double dwell. Each dwell is designed so that one performs about twice the magnitude of function of the other; that is, rotation of the cam 240 causes reciprocation of the plunger shaft 231 whereby the plunger 230 alternately forms a pocket in the capsule holding member by depressing it centrally and then tamps a capsule into the pocket formed thereby, the alternate strokes of the plunger 231 being such that the tamping stroke is fore-shortened 60 a distance equal approximately to the thickness of the capsule.

In order to impart flexibility to the action of the bottom end of the plunger and to prevent damage by engagement with the mandrels, it is provided with a universal arrangement or flexible sleeve joint comprising a casing 241 receiving the headed lower end of the shaft 231 and having a compression spring 242 contained in the casing in engagement with the head formed on the end of shaft 231. The casing is thus flexibly or swivelly mounted on the end of the shaft 231. At the bottom end of the universal head or joint 241 is a projection 243 constituting the plunger. With this arrangement the plunger 243 moves 75 adjacent the end of the chute 228 and performs

the function of first depressing the capsule holding member overlying the mandrel to form a pocket therein and then permitting a capsule coming down the chute 228 to enter the top of the pocket as the plunger is withdrawn, after which the plunger 243 tamps the capsule into the pocket. The capsules are fed down the chute 228 in timed relation to the operation of the plunger 243 so that each capsule rests against the plunger 243 during its upstroke after formation of the pocket (Fig. 10). The mandrel is provided with an opening sufficient in size to permit the formation of such a pocket in the capsule holding member as well as to permit the other operational functions of the plunger device.

Container feeding mechanism

Preferably, the containers used in practicing the present invention are of tube-like construction. They may be made from a web of material having a single longitudinal seam, a double web having oppositely disposed longitudinal seams, or they may be made from extruded plastic tubing or other suitable heat-sealable material. It is within the contemplation of the invention to feed prefabricated containers of any suitable type into the machine and place them around the mandrels which have been supplied with the patches and capsules ready for sealing to an inner wall surface thereof. However, a preferred embodiment of container producing mechanism is shown in the accompanying drawings (see Figs. 16, 17 and 18).

In Fig. 16 a continuously running tube 300 of plastic material, such as, for example, polyethylene, is shown being unwound from a mill roll 301 (see also Fig. 3). It is known that due to static or other conditions the interior surfaces of such a tube often adhere rather tenaciously together. It is desirable initially to effect a separation between the inner faces of such walls so as to facilitate opening of the ultimate tubular containers to facilitate slipping them over the mandrels. Therefore, the tube 300 is passed through an air-block arrangement comprising a series of spaced parallel rods or rollers 302 and at a suitable distance thereabove another group of similarly spaced rods or rollers 303. After the tube 300 has been initially threaded between the group of rollers 302 of the air-block, a bubble of air is injected with an hypodermic needle into the tube between the rollers 302 and 303 so as to expand the tube as shown at 304. Constantly drawing the tube between the two groups of rollers 302 and 303 effects an initial separation of the inner wall surfaces of the tube because of the presence of the air bubble which remains relatively fixed as the tube slides around it.

The tube is next passed around idler roller 305 and then between feeding rollers 306 and 307, 60 the roller 306 being mounted on the driven shaft 49. The tube next passes between a revolving cutting blade 308 and an anvil roller 309 and the tube is partially severed. A complete severance is not effected but the tube is permitted to remain attached at certain points. The continuous but partially severed tubing continues to advance over a belt conveyor mechanism indicated generally at 310.

The conveyor mechanism 310 comprises a continuous belt 311 passing around a driven pulley 312, rollers 313 and 314 and toward the rectilinear traverse of mandrels around a nose roller 315. Spaced hold-down rollers 316 are supported above the top flight of the belt 311 and bear on the con-

tinuously advancing tube material. The conveyor belt 311 travels at a slightly faster rate than the movement of the tubular material, as it is delivered to it, to iron out wrinkles, etc. by tension on the web and to assure proper alignment of the leading end of the partially severed material for operation of the opening device.

When the leading end of the partially severed tubing reaches the end of the top flight of the conveyor belt 311 it is necessary to break off or completely sever the first or leading tube section since it is still connected to the continuous tube by the small unsevered portions of the material. It is also necessary to separate the walls of this tube section at the forward end in order to strip the completely severed section over the mandrel which is advanced in its path carrying the capsule in the pocket formed in the associated holding member thereon and to position the container forming tube section thereover in position for sealing.

This is accomplished by means of a sliding or reciprocating device indicated generally at 317 (Figs. 16 and 18). This device or mechanism is mounted on suitable vertically spaced longitudinal bars or gibs 318 and 319 and includes a reciprocating head 320 carrying two opposed arms 321 and 322 the former being pivotally mounted on the upper portion of the head at 323 while the latter is fixed relative to the head on a lower, laterally extending arm 324. At their free ends the arms 321 and 322 are each provided with a suction member, or cup, 325 and 326, respectively, which are in opposed relation, on opposite sides of the tube material, when the head 320 is in fully retracted position. The vacuum cups 325 and 326 are connected to a cam-operated valve controlled vacuum means by passageways extending through the arms 321 and 322, and the head 320 to connecting lines 327 (Figs. 2 and 18). The arm 321 is urged toward arm 322 by a tension spring 328 connected to the forwardly extending arm 329 at one end and to a forwardly extending portion of the base of the head at the other end, the arm 329 being connected to the arm 321 and movable therewith about the pivot 323. The reciprocating head 320 is actuated by a link 330 connected at one end to the bottom of the head and at the other end to a link lever 331 which is pivoted to the bottom of the frame of the machine at 332. The link 331 is pivotally connected intermediate its ends to one end of a connecting link 333 the other end of which is pivotally mounted on a crank arm 334 which is in turn mounted on driving shaft 45.

Mounted on the free end of arm 321 above the suction cup 325 is a cam roller resting upon a movable cam arm 336 directly in the path of the roller. This cam arm has a camming surface 337 and is arranged to rise and fall as shown by the arrow at the end thereof for the purpose of bringing the suction cups 325 and 326 in closed position as the leading end of each tube section is guided between them. When the cam arm 336 drops downwardly the valve controlling the vacuum is operated by the controlling cam to cause the outer walls of the tube material to be engaged by the vacuum cups 325 and 326 to initiate opening of the leading end of the end tube section.

70 The cam arm 336 is suspended from one end of a lever arm 338 by means of parallel links 339 and 340. The lever arm 338 is pivotally mounted at 341 on the support arm 342 attached to the machine frame at 343. The other end of the lever arm 338 is pivoted to a connecting link 344 which

is connected at its opposite end to one end of a bell crank lever 345. The bell crank 345 is pivoted at 346 to the bottom of the arm 342 and has a cam follower 347 at the end of the other arm 348 which rides the camming surface of an end cam 349 on the driven shaft 23. The cam 349 causes raising and lowering of the end of the cam arm 336 as indicated by the arrow initially to separate the pick-up or suction heads 325 and 326 and also to subsequently restore them to closed tube gripping position. When the suction members 325 and 326 are advanced by the reciprocating head 320, the partially severed leading container forming tube length is completely separated from the end of the oncoming tube. As the cam roller 335 on the suction head 325 advances, it strikes the camming surface 337 of the cam arm 336 and the suction cups 325 and 326 are moved apart to separate the walls at the leading end of the tube length whereby the tube length can be stripped over the mandrel. Further advance of the arms 321 and 322 carries the tube length over the mandrel so that an inner wall surface thereof overlies the capsule in the pocket of the associated holding member on the mandrel. In Fig. 17 a 25 container forming tube length 350 is shown, in dotted line, stripped over a mandrel, the latter being indicated generally at 351.

As the arms 321 and 322 on the reciprocating head 320 carry the suction cups 325 and 326 to the end of their stroke to deposit the completely severed tube length, the suction is broken and the tube length is held down by oppositely disposed hold-down arms 352 (Figs. 7 and 8). The hold-down arms 352 are connected to a rock shaft 353. Centrally connected to shaft 353 is an extension 354 having a cam roller 355 for actuating the hold-down arms 352 to bring them into raised position. The hold-down arms 352 are normally retracted by a spring 356 mounted on the rock shaft 353 and connected to the extension arm 354.

The hold-down arms are raised when the cam roller 355 intercepts the projection 357 (Fig. 17) on one arm 358 of a bell crank lever pivoted at 359 on the bracket arm 342. The end of the other arm 360 of the bell crank is connected by a link 361 to a control arm 362 which is also pivoted at 348 on the bottom of the bracket arm 342 and which is provided with a cam roller 363 at its free end for riding the cam surface of a cam 364 on the driven shaft 23. This arrangement causes the hold-down arms 352 to be raised upwardly out of position to receive the tube length 350 as the latter is moved into position over the mandrel 351. After the tube length passes under the hold-down arms 352 they are then restored to container holding position. In the meantime, the suction cups 325 and 326, at the ends of the arms 321 and 322, are freed of the tube section by shutting off the vacuum and preferably injecting air in the vacuum line to assure release of the tube length from the vacuum cups and the cups 325 and 326 are returned to their initial starting position by the reciprocating head 320. At this point the suction cups 325 and 326 are still in spaced apart position to receive the next succeeding container tube length therebetween. The continued operation of the cam 349 drops the cam arm 336 a short distance, sufficient to bring the suction cups 325 and 326 to closed position with the leading end of the next tube length therebetween. The vacuum valve is then operated by the cam to create a suction to grip the

leading end of the next tube length and the cycle is repeated.

Sealing mechanism

5 After the container forming length of tube has been moved onto the mandrel as described, the intermittent arrangement, which carries the series of mandrels, advances the mandrel to the sealing station where the capsule holding member is sealed to the inner wall surface of the length of tube and preferably, simultaneously therewith, a transverse seal is provided on the trailing end of the tube length which forms the bottom for the container (see Figs. 1, 19 and 20).

15 The sealing mechanism for forming the transverse seal to complete the bottom of the container will first be described. It comprises an upper sealing element or iron 400 and a lower sealing element or iron 401, each of which contains a conventional electrical heating cartridge. The upper sealing iron 400 is connected to an upper sliding gib plate 402 and the lower sealing iron 401 is connected to a lower sliding gib plate 403. The upper sealing iron 400 is resiliently mounted on the gib plate 402 by means of a plurality of plungers 404, 405 and 406 slidably mounted in upper and lower plunger retaining yokes 407 and 408, respectively, which extend from the gib plate 402. Resilient action is provided by springs 409, 410 and 411 surrounding the plunger members 404, 405 and 406, respectively.

20 Projecting from the upper and lower yokes 407 and 408 is an extending bracket or arm 412. Vertically movable within the end of the arm 412 is a sealing plunger 413 resiliently mounted by means of a spring 414 surrounding the same. The bottom of the plunger 413 has a sealing iron indicated generally at 415 provided with a sealing face 416 which is undercut, leaving a marginal sealing surface for marginally sealing the capsule holding member around the capsule to the inner surface of the tube wall. The sealing iron 415 is likewise provided with conventional electrical cartridges for heating the same.

25 In order to permit sealing of the capsule holding member to the tube wall it is necessary to withdraw the hold-down arm or member 417 (Fig. 8) out of the path of the sealing iron 415. The hold-down member 417, which retains the capsule holding or retaining member in position on the mandrel from the time of its deposit thereon until the sealing operation, is slidably as well as pivotally mounted on the mandrel 351.

30 The hold-down arm 417 is pivotally mounted by shaft 418 on a slide gib plate 419 which is mounted for sliding movement on side guides 420 in the lower rear portion of the mandrel 351. The hold-down arm 417 is urged into its operative position by a coil spring 421 around the shaft 418. An upwardly projecting arm 422 on the end of shaft 418 is provided with a cam follower 423 which is adapted to be engaged by a cam rail 424 on the main frame of the machine (Fig. 2). The gib plate 419 is normally held in the forward position by a pair of tension springs 425 secured at one end of the gib plate and at the other end to a forward portion of the mandrel 351. The gib plate 419 is provided with a cam follower 426 which is adapted to be engaged by the cam rail 427 on the main frame of the machine (Fig. 2). The cam rail 424 is mounted so that it engages the cam follower 423 just prior to the movement of the mandrel 351 into position to receive the capsule holding member and pivots the hold-down arm 417 to an out-of-the-way position until the holding member is deposited on

the mandrel. Movement of the mandrel to the next station releases the cam follower 423 from the rail 424 and permits the hold-down arm 417 to move into holding engagement with the capsule retaining member by action of the coil spring 421. When the mandrel 351 is subsequently moved to the sealing station for the sealing operation the cam rail 427 engages the cam follower 426 prior to arrival of the mandrel at the sealing station and retracts the hold-down arm 417 just prior to the sealing operation.

The sealing mechanism preferably is operated by a cam actuated compound linkage arrangement. A suitable arrangement is shown in Figs. 1 and 20 wherein a rotatable cam 428 on the driven shaft 25 (Fig. 1) contacts a cam follower 429 secured to one arm 430 of a bell crank which is pivotally mounted on a cam stud 431. The other arm 432 of the bell crank is connected by means of a link 433 to a link pin 434 secured to the lower gib plate 403. Connected to the link pin 434 is a lower sealer operating link 435 connected to a toggle arm 436 pivotally mounted on a fixed pivot stud 437 between the upper and lower gib plates 402, 403. The other end of the toggle arm 436 is connected to the lower end of an upper sealer operating link 438. The upper end of the link 438 is connected to the upper gib plate 402 by a link stud 439. Actuation of the cam 428 causes this compound linkage arrangement to draw the sealing irons 400 and 401 together to effect the transverse seal and close the tube section, thereby forming the bottom of the container. Simultaneously therewith the sealing iron 415 performs its sealing operation whereby the capsule holding member is secured to the inner wall surface of the container with the capsule therebetween.

A pair of upper and lower container stripper guides 440 and 441, respectively, are fixedly mounted adjacent the sealing portion of the irons 400 and 401. As these sealing irons 400 and 401 are spread apart after effecting the sealing operation the stripper guides 440 and 441 prevent the sealed portion of the container from sticking to the irons.

Mounted within each mandrel 351 is a sealing iron anvil 442 of suitable resilient material, such as a felt washer, which will be sufficient to absorb the thrust of the sealing iron 415, also which will tend to prevent adhesion of the underside of the capsule holding member thereto.

In order to interrupt the operation of the sealing mechanism in the event a mandrel is moved to the sealing station without having a container forming tube length positioned thereon a pivotally mounted arm 443 (Fig. 2) is provided having on its forward end a wheel 444 which is engaged by the top of the mandrel as it moves into the sealing station. Absence of the tube material on the mandrel completes an electrical circuit by contact of the wheel with the mandrel and actuates a solenoid to interrupt the operation of the sealing mechanism.

The mechanism carrying the mandrels moves them to the end of the machine where a completed container, as shown in Figs. 27 and 28, is then stripped therefrom by the hand of the operator, as indicated in Fig. 26, after being released by the container hold-down arms 352 by engagement of cam roller 355 with the cam rail 445 (Fig. 1).

Each mandrel continues along the lower flight of the rectilinear traverse and, on being raised to upward position, starts once again along the

upper flight thereof. The cam bar rail 424 (see Figs. 1, 2, 3 and 8) intercepts the cam roller 423 on the projecting arm 422 which controls the hold-down member 417 and raises the same upwardly away from the mandrel as shown in Fig. 22 so that the mandrel can again receive another capsule holding member and the cycle of operation is repeated.

Operation

Briefly summarizing the operation of the machine and referring in particular to Figs. 4, 5 and 6 (Capsule Holding Member Perforating and Cutting Mechanism) it will be seen that a continuous web of material 100 is passed over rollers 102 and 103 and perforated in the perforating mechanism indicated generally at 105 by rapid penetration thereof by the gang of needles 113.

The perforated tape is then continuously drawn between rollers 116 and 117 and a slack 118 is formed in the web of material by operation of the rollers 119 and 120 which change the feed from a continuous to an intermittent motion in order to present sections of the material to be severed by the knife 118 in timed relation for delivery to each mandrel as it passes adjacent the cutting knife whereby a capsule holding member is deposited over the apertured resilient anvil member 442 in each successive mandrel. It will be noted from Fig. 6 that the cam arm rail 424 has raised the hold-down arm 417 out of the way of the knife but that the hold-down 417 will be moved to operative position by the action of springs 421 and 425 (Fig. 8) as the cam roller 423 follows the curvature of the cam rail 424.

Referring now to Figs. 10 to 15 (Capsule Feeding Mechanism) it will be seen that the oscillatable or rocking hopper 200 causes an aligned stack of capsules 202 to be passed through the conduit 221. The rocking of the hopper 200 is brought about by the clover shaped cam 210, on drive shaft 31, actuating the cam roller 214 through the links 211 and 215. At the same time the heart-shaped cam 224, which is secured to the same drive shaft 31, actuates the roller 223 on the plate 222. Attached to plate 222 is the capsule injector 226 (see Figs. 11 and 13) which is reciprocated to pick up a capsule 202 in the U-shaped portion 227, and deposit it in the delivery chute 228. Also mounted adjacent the capsule feeding mechanism is a plunger mechanism 230 (see Figs. 10 and 12) which is vertically reciprocable and has a double function. The plunger end 243 on the first downward stroke pushes a portion of the capsule holding member 442 through the opening in the anvil member 442 to form a pocket therein. Thereafter, a capsule 202 moves along the inclined chute 228 and is dropped into the top of the pocket by gravity. On the return stroke, the plunger end 243 tamps or pushes the capsule 202 into the bottom of the pocket. The mandrels are then carried along the rectilinear traverse and pick up a tubular container construction thereon from the Container Feeding Mechanism.

The Container Feeding Mechanism which is illustrated (Figs. 16, 17 and 18) in the present machine supplies container forming tubular sections by unwinding from a mill roll of tubular container stock a web 300 as shown in Fig. 16. This web is threaded between the bars 302 and 303 of the air-block, a bubble of air is inserted therein as at 304, and the tube is passed around idler roller 305 and between feed rollers 306 and 307. As the tube passes beneath the cutting knife 308 it is partially severed across its width.

The series of container tubes, held together by small sections of unsevered material, are fed through the conveyor mechanism 310 along the upper flight of the belt 311 to iron out the wrinkles, etc. and present the leading end in proper position for movement onto the mandrel. As each leading container forming tube section presents itself at the end of the conveyor flight the reciprocating head 320, having arms 321 and 322 with suction cups 325 and 326 on the end thereof, operates to open the leading end of the tube section, break it loose from the continuous tube and strip it over the mandrel so that an inner wall surface thereof overlies each capsule and its holding member ready to be sealed in the Sealing Mechanism.

The Sealing Mechanism (Figs. 19 and 20) simultaneously seals the capsule holding member marginally to the inside wall of the tube section by means of the sealing iron 415 and the sealing irons 400 and 401 transversely seal the trailing end of the tube section to provide a completed container whereupon the same is stripped from the mandrel ready for use.

It will thus be seen that the objects hereinbefore set forth may readily and efficiently be attained, and since certain changes in carrying out the above method and in the constructions set forth, which embody the invention may be made without departing from its scope, it is intended that all matter contained in the above description or shown in the accompanying drawings shall be interpreted as illustrative and not in a limiting sense.

Having described my invention what I claim as new and desire to secure by Letters Patent is:

1. A machine for making containers having a capsule of dispersible material secured against an inner wall surface thereof by a holding member that will permit the material to be dispersed within the container, which comprises movable mandrels, mechanism cooperatively associated with said mandrels for feeding capsule holding members successively onto said mandrels in capsule receiving position, mechanism for feeding capsules successively onto said holding members, mechanism for feeding container formations relative to said mandrels so that inner wall surfaces thereof overlie the capsules and the holding members therefor when the container formations are on the mandrels, and mechanism for securing said holding members to said inner wall surfaces of said container formations to hold said capsules in position.

2. A machine as defined in claim 1 wherein said mandrels are provided with movable hold-down elements for retaining said capsule holding members on said mandrels in capsule receiving position.

3. A machine as defined in claim 1 wherein said mandrels are provided with movable hold-down elements for retaining said capsule holding members on said mandrels in capsule receiving position, said hold-down elements and said mandrels each having a hole therein in registry with each other and a plunger mechanism operatively associated with said mandrels to move through the hole in the hold-down element and depress a portion of the capsule holding member into the hole in the mandrel to provide a capsule receiving pocket therein.

4. A machine as defined in claim 1 wherein the capsule feeding mechanism comprises a movable hopper and means for feeding individual capsules therefrom and successively delivering

the capsules onto the capsule holding members on the mandrels.

5. A machine as defined in claim 1 wherein the capsule feeding mechanism comprises a movable hopper having an opening therein for discharging individual capsules therefrom, actuating means for imparting to said hopper a uniform movement to aid in the discharge of the capsules through said opening, and means to deliver the discharged capsules successively to the capsule holding members on said mandrels.

6. A machine as defined in claim 1 wherein the capsule feeding mechanism comprises a supply hopper having a single capsule discharge opening, a flexible spring conduit connected at one end to said discharge opening for holding a stack of the capsules, a capsule selecting member and a gravity feed chute, said capsule selecting member being operable to successively deliver the bottom capsules in the stack to the chute for gravity feed onto the capsule holding members on the mandrels in timed relation to the movement of the mandrels.

7. A machine as defined in claim 1 wherein the capsule feeding mechanism comprises a reciprocable plunger device for first forming a pocket in the capsule holding member on each mandrel as the mandrel moves into position to receive the capsule and thereafter tamping the capsule into the pocket so that it is partially surrounded by the capsule holding member.

8. A machine as defined in claim 1 wherein the capsule feeding mechanism comprises a reciprocable plunger device having a flexible plunger head, means for reciprocating said plunger device to alternately move the head different predetermined distances, said plunger head first engaging the capsule holding member on each mandrel as the mandrel moves into capsule receiving position and depressing the material to form a pocket therein, said plunger head thereafter engaging the capsule delivered to said holding member and tamping it in the pocket.

9. A machine as defined in claim 8 wherein the capsule feeding mechanism also includes means for feeding capsules successively against said plunger head while it is operating to form the pocket in the holding member whereby a capsule is delivered by gravity into the pocket and tamped therein by the succeeding movement of the plunger.

10. A machine as defined in claim 1 wherein the capsule feeding mechanism comprises a rockable hopper, a gravity chute, means cooperating with the hopper to deliver individual capsules into the chute, a combined pocket forming and tamping device including a reciprocating plunger, means for reciprocating the plunger whereby alternate strokes thereof are foreshortened a distance equal approximately to the thickness of a capsule, said plunger operating on one stroke to engage the capsule holding member on the mandrel as each mandrel moves into position for receiving a capsule to form a pocket therein, said capsule delivery chute terminating adjacent the path of the plunger and the delivery means therefor being timed to deliver a capsule against the plunger while it is forming the pocket whereby the capsule falls by gravity into the pocket as the plunger is withdrawn therefrom and is thereafter tamped into the pocket by the succeeding stroke of the plunger.

11. A machine as defined in claim 1 wherein the mechanism for feeding the container formations includes means for feeding a continuous

tube of container forming material, an air block for separating the inner walls of the tube, means for cutting the tube into container forming lengths and means for stripping the lengths onto the mandrels so that an inner wall thereof overlies the capsule and its holding member.

12. A machine as defined in claim 1 wherein the mechanism for feeding the container formations includes means for continuously feeding a tube of container forming material, means for partially severing the tube into container forming sections, means for ironing out said partially severed tube and delivering the leading end thereof in position for feeding onto the successive mandrels, and successively operating means for completely separating the leading container forming section from the tube and delivering the separated section onto the respective mandrel which has been moved into position to receive the same.

13. A machine as defined in claim 1 wherein the mechanism for feeding the container formations comprises a reciprocating head, suction members carried by said head and movable relative to each other, means for successively delivering lengths of container forming tube material into position with the leading edges thereof adjacent the suction members, cam means in the path of movement of the suction members for controlling their movement relative to each other, and means for reciprocating said head whereby opposed walls of successive tube lengths are gripped by said suction members and moved apart as the head is moved toward a mandrel to strip the tube length onto the mandrel so that one wall thereof overlies the capsule and its holding member on the mandrel.

14. A machine as defined in claim 1 wherein the mechanism for feeding the container formations includes means for feeding a continuous tube of container forming material and partially severing the same into container forming tube lengths, a continuous conveyor having cooperating hold-down members for straightening out the partially severed tube and guiding the leading end thereof into predetermined position relative to the oncoming mandrels, and reciprocating means for successively separating the leading tube length from the tube, opening the end thereof and stripping the same onto a mandrel so that an inner wall surface thereof overlies a capsule and its holding member on the mandrel.

15. A machine for making heat-sealable containers having a capsule of dispersible material secured against an inner wall surface thereof by a heat-sealable holding member that will permit the material to be dispersed within the container, which comprises movable mandrels, mechanism cooperatively associated with said mandrels for cutting capsule holding members from a web of heat-sealable material and feeding said holding members successively onto said mandrels in capsule receiving position, mechanism for feeding capsules successively onto said holding members, mechanism for feeding container formations onto said mandrels so that an inner wall surface of each container overlies a capsule and its holding member on each mandrel, and mechanism for heat-sealing said holding members to the inner wall surfaces of said container formations to hold said capsules in position.

16. A machine for making heat-sealable containers of tube-like construction transversely sealed at one end and having a capsule of dispersible material secured against an inner wall

surface thereof by a heat-sealable holding member that will permit the capsule to be dispersed within the container, which comprises movable mandrels, mechanism cooperatively associated with said mandrels, including a device for successively perforating a web, cutting the same into capsule holding members, and feeding said holding members onto said mandrels in capsule receiving position, mechanism for feeding capsules successively onto said holding members, mechanism for feeding tube-like container formations onto said mandrels so that an inner wall surface thereof overlies a capsule and its associated holding member on each mandrel, and mechanism for heat-sealing said holding members to said inner wall surfaces of said tube-like container formations to hold said capsules in position.

17. A machine as defined in claim 16 wherein the mechanism associated with said mandrels for forming the capsule holding members also includes means for initially feeding the web continuously while it is being perforated, and means for thereafter feeding the web intermittently to permit capsule holding members of uniform length to be cut therefrom and to be deposited in timed relation onto said mandrels.

18. A machine for making heat-sealable containers of tube-like construction transversely sealed at one end and having a capsule of dispersible material secured against an inner wall surface thereof by a heat-sealable holding member that will permit the contents of said capsule to be dispersed within said container, which comprises movable mandrels, mechanism cooperatively associated with said mandrels for feeding capsule holding members successively onto said mandrels in capsule receiving position, mechanism for feeding capsules successively onto said holding members, mechanism for feeding container formations onto said mandrels so that inner wall surfaces thereof overlie the capsules and their respective holding members, mechanism for heat-sealing the holding members to the inner wall surfaces of said container formations to hold said capsules in position, and mechanism for transversely heat sealing a marginal end of said container formations.

19. A machine for making heat-sealable containers of tube-like construction transversely sealed at one end and having a capsule of dispersible material secured against an inner wall surface thereof by a heat-sealable holding member that will permit the contents of said capsule to be dispersed within said container, which comprises movable mandrels, mechanism cooperatively associated with said mandrels for feeding capsule holding members successively onto said mandrels in capsule receiving position, mechanism for feeding capsules successively onto said holding members, mechanism for feeding tube-like container formations onto said mandrels so that inner wall surfaces thereof overlie the capsule and its holding member on the respective mandrels, and mechanism for heat-sealing a holding member to the inner wall surface of a container formation to hold the capsule in position, and simultaneously heat sealing one end of a container formation to complete the container.

20. In a container forming machine, a plurality of intermittently moving mandrels, said mandrels having means thereon for receiving a capsule holding member and an enveloping container formation, means for supplying successively to

the mandrels a capsule holding member, means for forming a pocket in the capsule holding member, means for positioning a single capsule in the pocket, means for providing a tube-like container formation and stripping it onto the mandrel with a wall thereof overlying the capsule and its holding member, and means for securing the capsule holding member to the wall of the container formation.

21. In a container forming machine, a mandrel, means for moving the mandrel past a series of work stations, a mechanism at one of the work stations for supplying the mandrel with a perforated capsule retaining member, a mechanism at another work station for forming a pocket in the retaining member and inserting therein a capsule, a mechanism at a third work station for supplying a tube-like container formation and positioning it on the mandrel with an inner wall thereof overlying the capsule, and a mechanism at a fourth work station for securing the capsule retaining member to the wall of the container formation.

22. A container forming machine as recited in claim 21 wherein the mechanism at the fourth work station includes means for closing one end of the container formation.

23. In a machine for making heat-sealable containers of tube-like construction transversely sealed at one end and having a capsule of dispersible material secured against the inner surface of one wall thereof by a heat-sealable holding member that will permit the capsule to be dispersed within said container, movable mandrels, means associated with said mandrels for perforating a continuously running web of material, and means for cutting successive lengths from said web to form holding members for the capsules and for delivering said holding members successively onto said mandrels in capsule receiving position.

24. In a machine for making heat-sealable containers of tube-like construction transversely sealed at one end and having a capsule of dispersible material secured against the inner surface of one wall thereof by a heat-sealable holding member that will permit said capsule to be dispersed within said container, movable mandrels, means for delivering capsule holding members onto said mandrels, a movable hopper for containing a supply of capsules, said hopper having an opening therein for discharging individual capsules therefrom, a spring conduit connected to said hopper for receiving a stack of capsules through said discharge opening, and means for feeding capsules from the stack successively onto said holding members on said mandrels.

25. In a machine for making containers of tube-like construction transversely sealed at one end and having a capsule of dispersible material secured against the inner surface of one wall thereof by a folding member that will permit said material to be dispersed within said container, movable mandrels, mechanism cooperatively associated with said mandrels for delivering to successive mandrels a capsule holding member and a capsule thereon, mechanism for delivering to a predetermined position relative to the mandrels a tube-like container formation, and mechanism including a reciprocating head carrying opposed gripping members for separating the leading ends of said container formations and for feeding said container formations onto said mandrels so that an inner wall surface of each con-

tainer formation overlies the capsule and its holding member on the respective mandrel.

26. In a machine for making containers of tube-like construction transversely sealed at one end and having a capsule of dispersible material secured against the inner surface of one wall thereof by a holding member that will permit said material to be dispersed within said container, movable mandrels, mechanism cooperatively associated with said mandrels for delivering to each of said mandrels a holding member and a capsule thereon and mechanism for delivering a tube-like container forming member onto each of said mandrels including a reciprocating head, opposed arms on said head, one of which is pivotally mounted at one end on said head and both of which terminate with opposed suction cups at their free ends, a pivotally mounted cam member disposed in the path of travel of said first named arm and in contacting relation thereto, whereby said suction cups are operated to grip the opposite walls of the leading end of a container forming member in spaced apart relation during reciprocation of said head to hold said walls in separated position while the container forming member is moved onto the respective mandrel and whereby said cups are thereafter restored to initial container receiving position on the return stroke of said head by operation of said cam.

27. In a machine for making heat-sealable containers of tube-like construction transversely sealed at one end and having a capsule of dispersible material secured against the inner surface of one wall thereof by a heat-sealable holding member that will permit the contents of said capsule to be dispersed within said container, movable mandrels, mechanism for sealing a capsule holding member positioned on a mandrel to the wall of a tube-like container positioned over the same on the mandrel, including a heat sealing head having a marginal sealing face whereby heat and pressure can be applied simultaneously to the outer wall surface of said container and marginally of said underlying capsule holding member to bond the same in capsule holding position.

28. In a machine for forming containers and securing therein a capsule of material which is adapted to be dispersed within the container after the container has been filled with a commodity, a traveling mandrel, a mechanism adjacent the path of travel of the mandrel for feeding, perforating and cutting into strips a relatively narrow web of fibrous material to form capsule retaining members, said mandrel and said mechanism being so arranged and operated that the capsule retaining members are successively delivered onto the mandrel and said mandrel having hold-down means thereon operated to engage and hold thereon the capsule retaining member for a portion of the travel of the mandrel.

29. A method of making containers having a capsule of dispersible material secured against an inner wall surface thereof by a holding member that will permit the contents of the capsule to be dispersed within the container, which comprises feeding holding members into capsule receiving position, feeding capsules successively onto said holding members, feeding containers with respect to said holding members so that an inner wall surface of each container overlies a capsule and a holding member associated therewith, and sealing said holding members to the

inner wall surface of said containers to hold said capsules in position within said containers.

30. A method for making containers having a capsule of dispersible material secured against an inner wall surface thereof by a holding member that will permit the contents of the capsule to be dispersed within the container, which comprises cutting holding members from a web of material and feeding them successively into capsule receiving position, feeding capsules successively onto said holding members, feeding containers with respect to said holding members so that the inner wall surface of each container overlies a capsule and its holding member, and sealing the holding members to the inner wall surface of each container to hold the capsule in position within the container.

31. A method for making heat-sealable containers having a capsule of dispersible material secured against an inner wall surface thereof by a heat-sealable holding member that will permit the material to be dispersed within the container, which comprises perforating holding members and feeding them successively onto receiving members in capsule receiving position, feeding said capsules successively onto the holding members, feeding container forming members onto the receiving members so that an inner wall surface of each container forming member overlies a capsule and its holding member on a receiving member, and heat-sealing the capsule holding members to the inner wall surfaces of the containers to hold the capsules in position within the containers.

32. A method for making heat-sealable containers of tube-like construction having a capsule of dispersible material secured against the inner surface of one wall thereof by a heat-sealable patch-like member that will permit the material to be dispersed within the container, which comprises perforating a moving web, cutting patch-like members therefrom and simultaneously feeding said patch-like members successively onto receiving members in capsule receiving position, feeding capsules successively onto said patch-like members, feeding containers onto said receiving members so that one inner wall surface thereof overlies the capsule and patch-like member, and heat-sealing the patch-like members to the inner wall surfaces of the containers to hold the capsules in position within the containers.

33. A method for making heat-sealable containers of tube-like construction transversely sealed at one end and having a capsule of dispersible material secured against the inner surface of one wall thereof by a heat-sealable holding member that will permit the capsule to be dispersed within the container, which comprises perforating a continuously running web of capsule holding material, changing the motion of feed of the web to an intermittent motion, cutting holding members therefrom and delivering the same successively onto receiving members in capsule receiving position, feeding capsules successively onto the holding members, feeding container forming tubes onto the receiving members so that inner wall surfaces thereof overlie the capsules and their holding members, heat-sealing the holding members to the inner wall surfaces of the container forming tubes to hold the capsules in position within the same, and heat-sealing transversely one end of the container forming tubes.

34. A method for making containers having a capsule of dispersible material secured against an

inner wall surface thereof by a holding member that will permit the capsule to be dispersed within the container, which comprises successively feeding capsule holding members into predetermined position for receiving capsules thereon, providing a supply of capsules and feeding the capsules successively onto the holding members, feeding container formations relative to the holding members so that said inner wall surfaces thereof overlie the capsules and their holding members, and sealing the holding members to the inner wall surfaces of the container formations to hold the capsules in position within the container formations.

35. A method for making heat-sealable containers having a capsule of dispersible material secured against an inner wall surface thereof by a heat-sealable holding member that will permit the capsule to be dispersed within the container, which comprises feeding capsule holding members into predetermined position for receiving capsules thereon, providing a supply of capsules, aligning them in continuously stacked arrangement, feeding individual capsules from the bottom of the stack and delivering them onto successive holding members, feeding container forming members relative to the capsule holding members so that an inner wall surface of each container member overlies a capsule and its holding member, and heat-sealing the holding members to inner wall surfaces of the container members to hold the capsules in position within the containers.

36. A method of making containers having a capsule of dispersible material secured against an inner wall surface thereof by a holding member that will permit the capsule to be dispersed within the container, which comprises feeding holding members into capsule receiving position, providing a supply of capsules, aligning them in stacked arrangement, selecting individual capsules from the bottom of the stack and tamping said capsules into position in said holding members so that said holding members partially surround said capsules, feeding container forming members and the associated capsules and their holding members relative to each other to bring one inner wall surface of each container member into overlying relation to a capsule and its holding member, and sealing the holding members to the inner wall surfaces of the container members to hold the capsules in position within the containers.

37. A method for making containers having a capsule of dispersible material secured against an inner wall surface thereof by a holding member that will permit the capsule to be dispersed within the container, which comprises feeding capsule holding members into position for receiving capsules thereon, providing a supply of capsules, aligning them in continuously stacked arrangement, removing individual capsules from the bottom of said stack, forming a pocket in each capsule holding member by depressing it centrally thereof, feeding and then tamping a capsule into the pocket formed therein, moving the holding members into position for receiving container forming members, feeding container forming members into position over the respective capsule holding members so that an inner wall surface of each of said container forming members overlies a capsule and its holding member, and sealing the holding members to the inner wall surfaces of the container forming members to hold the capsules in position within the same.

38. In the manufacture of containers for oleaginous materials wherein a capsule containing coloring matter is carried by a supporting membrane between the opposed walls of the container whereby it may ultimately be broken in order to disperse said matter in said material, the improvement comprising providing a supporting membrane and placing a capsule thereon, providing a container and positioning said membrane with said capsule relative to the inside of said container so that the capsule is disposed between an inner surface of one wall of the container and the membrane, and securing the membrane to said surface to maintain said capsule in said position.

39. A method for making containers having a capsule of dispersible material secured against an inner wall surface thereof by a holding member that will permit the capsule to be dispersed within the container, which comprises feeding holding members into capsule receiving position, feeding capsules onto said holding members, providing a continuously unwinding tube of sealable material, cutting container forming tubes therefrom and feeding said container tubes onto said holding members so that one inner wall surface of each container tube overlies a capsule and its holding member, and sealing said holding members to the inner wall surfaces of the container tubes to hold the capsules in position within the same.

40. A method for making heat-sealable containers of tube-like construction transversely sealed at one end and having a capsule of dispersible material secured against an inner wall surface thereof by a heat-sealable holding member that will permit the capsule to be dispersed within the container, which comprises feeding holding members into capsule receiving position, feeding capsules successively onto said holding members, partially severing predetermined sections of a continuous length of tube stock into container forming tube sections, separating said partially severed tube sections from said continuous length of tube stock, feeding said tube sections onto said receiving members so that an inner wall surface thereof overlies a capsule and its holding member, heat-sealing said holding members to the inner wall surfaces of the tube sections to hold the capsules in position therein, and heat sealing transversely one end of the tube sections.

41. A method for making heat-sealable containers of tube-like construction transversely sealed at one end and having a capsule of dispersible material secured against an inner wall surface thereof by a heat-sealable holding member that will permit the capsule to be dispersed within the container, which comprises feeding holding members into capsule receiving position, feeding capsules onto successive holding members, providing a continuous tube of heat-sealable material, partially severing said tube into container forming sections of predetermined length, separating the leading end of said tube sections, feeding said tube sections onto said holding members so that an inner wall surface thereof overlies a capsule and its holding member, heat-sealing said holding member to the inner wall surfaces of said tube sections to hold the capsules in position therein, and simultaneously therewith sealing transversely one end of said tube sections.

42. A method for making heat-sealable containers of tube-like construction transversely sealed at one end and having a capsule of dispersible material secured against an inner wall

surface thereof by a heat-sealable holding member that will permit the capsule to be dispersed within the container, which comprises feeding holding members into capsule holding position, feeding capsules onto successive holding members, feeding open-ended tube sections onto said holding members so that an inner wall surface of each section overlies a capsule and its holding member, heat-sealing said holding member to the inner wall surface of each container to hold the capsule in position therein while simultaneously sealing transversely one end of the tube section.

43. A method of making heat-sealable containers of tube-like construction transversely sealed at one end and having a capsule of dispersible material secured against an inner wall surface thereof by a heat-sealable holding member that will permit the capsule to be dispersed within the container, which comprises feeding holding members into capsule holding position, feeding capsules onto successive holding members, feeding container formations relative to said holding members so that an inner wall surface thereof overlies a capsule and its holding member, heat-sealing the holding member to the inner wall surface of each container formation to hold the capsule in position therein by applying heat and pressure to the outer wall surface of the container formation and marginally of the underlying capsule holding member, and simultaneously transversely sealing one marginal end of the container formation.

44. A method of making a container of flexible heat-sealable material comprising providing a tube-like container forming member, assembling a perforate patch-like holding member with a capsule of material adapted to be dispersed in the container, arranging the capsule and its holding member within the tube-like member so that the capsule is adjacent the inner surface of a wall thereof, and heat-sealing the holding member to the wall of the tube-like member.

45. A method of making a container of flexible material comprising assembling a capsule of material which is adapted to be dispersed in the container and a retaining member therefor, providing a length of tube-like container material, positioning the capsule and its retaining member in juxtaposed relation to the inner surface of a wall of the tube length, and securing the capsule retaining member to the wall so that the capsule may be crushed and the material dispersed within the tube length.

46. A method of making a container of flexible material comprising: providing a capsule of material adapted to be dispersed in the container and a holding member therefor; providing a tube-like section of container forming material; moving the tube section, the capsule and the holding member relative to each other to bring the capsule between the holding member and an inner wall surface of the tube section; and securing the holding member to the wall surface so that the dispersible material may pass into the container upon rupture of the capsule.

47. A method of forming a flexible container and securing therein a capsule of dispersible material so that the capsule may be ruptured and the material dispersed within the container which method comprises: providing a tube-like open ended container formation; assembling a capsule of dispersible material and a retaining member therefor within the container formation so that the retaining member may be secured to an inner wall surface of the container formation in par-

tially enveloping relation to the capsule; securing the retaining member to the wall surface; and transversely closing one end of the container formation.

48. A method of forming containers and securing therein a capsule of dispersible material which comprises intermittently moving a plurality of mandrels past a series of work stations located along an endless path, delivering patch-like capsule holding members onto the mandrels at one work station, forming a pocket in each capsule holding member and feeding a capsule into the pocket at another work station, delivering a tube-like container formation onto each mandrel so that a wall thereof overlies the capsule and its holding member at another station, and securing the holding member to the wall of the container formation at a subsequent station.

15

49. A method of forming a container and securing therein a capsule of material adapted to be dispersed within the container comprising intermittently moving a mandrel past a series of work stations, forming a capsule holding strip of material and placing it on the mandrel at one station, placing a capsule on the holding member at another station, forming an open-ended container tube section and placing it over the mandrel at another station with a wall of the tube section overlying the holding strip, and securing the holding strip to the tube section while closing one end of the tube section at a final forming station.
